UNITED STATES PATENT OFFICE

ANDREW A. DOWNEY, OF ARMSTRONG, ILLINOIS.

FARM-GATE.

SPECIFICATION forming part of Letters Patent No. 605,948, dated June 21, 1898.

Application filed September 24, 1897. Serial No. 652,896. (No model.)

To all whom it may concern:

Be it known that I, ANDREW A. DOWNEY, of Armstrong, in the county of Vermilion and State of Illinois, have invented certain new and useful Improvements in Farm-Gates, of which the following is a specification.

This invention is designed to improve various details in swinging gates adapted to be opened from a vehicle. It is exemplified in the structure hereinafter described, and it is defined in the appended claim.

In the drawings forming part of this specification, Figure 1 is a perspective representation of so much of a gate as is needed to exemplify my improved opening and closing mechanism. Fig. 2 is a plan of the complete gate. Fig. 3 is a side elevation of a fragment of the gate and a post thereof, showing the latch and catch of the gate. Fig. 4 is an elevation of a portion of the inner surface of the catch-post, showing the catch in position thereon. Fig. 5 is a perspective representation of one member of the catch.

In constructing a gate in accordance with my invention I set a hinge-post, as 1, and fasten a cross-head, as 2, on the upper end of the post. The cross-head is hollow or of open structure, and it is preferably supplied with a pair of horizontal pulleys near its center and with a vertical pulley at each end. The gate 4 is made of any desired size and in any preferred way, and it is hinged at its upper end to post 1, substantially as shown in Fig. 1. The member 3 of the hinge is screwed into the post or otherwise secured thereto, and its bearing-surface extends upward or in a vertical direction. The member 5 is looped horizontally around the vertical portion of member 3, and its ends are made to embrace the upper inner corner of the gate. The distance of the vertical portion of member 3 from post 1 and the length of the loop of member 5 provide for tilting motion in the gate, which is utilized in a manner hereinafter described to detach the gate-latch from its catch.

A post 10 is fixed in the ground on one side of the hinge-post 1, and a post 12 is set an equal distance on the opposite side. These posts extend higher than the gate and the hinge-post, and they provide supports on which pivot bars 9 and 11, respectively. The bars terminate above the center of cross-head

2, and a rope or other flexible line runs from the end of one downward through an end of the cross-head obliquely over to the gate, 55 thence to and through the opposite end of the cross-head, and thence to the inner end of the opposite bar. The ran of the rope is illustrated in Fig. 1, where 8, 8^a, 8^b, 8^c, and 8^d represent the consecutive diversions, and it will 60 be observed in this figure that the rope runs from a bar to the end of the cross-head opposite such bar and that in consequence of such arrangement the gate must always swing away from the person who is manipulating 65 a bar to move the gate. The rope runs to the gate, as shown at 8^a and 8^c, and over it, as shown at 8^b. The end bars of the hinge-loop 5 are slightly curved at 6 to admit the rope 70 between the bars and the sides of the gate, and when the bolts 7 are tightened the rope is held against slipping. Whenever the rope through wear or other cause becomes disadjusted, the bars of the loop may be loosened and the rope be shifted over the upper edge 75 of the gate to the proper position to neutralize the disadjustment.

The lower hinge of the gate may be made somewhat as shown in Fig. 1, where 18 represents a fixed member and 19 a swinging member, and the swinging of the gate is effected as follows: A person drives or rides up to a bar 11, for instance, and pulls down on the outer end of the bar through the instrumentality of a depending line or link. The force 85 thus exerted is applied primarily to tilting the gate toward the upper end of the hinge-post, thereby raising the latch from contact with the catch, and secondarily to swinging the gate open in a direction away from the 90 manipulator. The gate stands in a horizontal position when the latch is in engagement with the catch, and its swinging end is raised and the vertical axis shifted when the latch is raised clear of the catch. This develops a 95 tendency in the gate to swing toward the opposite side of the post, and when a very slight pull is exerted through the rope it will swing off a dead-center and under ordinary circumstances open automatically. In other words, 100 the pull necessary to raise the latch clear of the catch carries the gate to a position from which its natural tendency is to swing open. On each side of the hinge-post 1 is a post

20, having a catch 21, and with one or the other of these catches the latch engages when the gate is opened. In order to close the gate, 5 and this is accomplished by tilting the gate upward and so disarranging its vertical pivot or hinge line that the gate will tend to swing closed.

The latch and catch are shown in detail in Figs. 3, 4, and 5, and they have the following peculiarities: The latch 14 is connected pivotally with the gate at 17, and its engaging end projects beyond the outer edge of the gate. Its downward motion is limited, it may be 15 moved freely upward, and it is held normally in its lowest position by force of gravity. The catch is preferably formed of a rod which is bent to form the oblique side loops 15^a, the central catch-depression 15^b, and the post- 20 penetrating points 15^c. The points are driven into the post 13, the loops 15^a form inclines up which the latch rides in act of closing the gate, and the recess 15^b holds the latch and the gate against sidewise motion. As the 25 gate usually closes with considerable force, there is danger of its passing the catch-post and swinging open toward the other side thereof if something is not provided to counteract this tendency. To provide for this, I 30 place a stop 16 above the center of the catch, with its lower end extended slightly into the

recess 15^b. This arrests the latch as it passes over the catch, stops the motion of the gate, and causes the latch to drop into the recess, where it is retained by gravity until the gate 35 is raised in the manner described or the latch is raised by hand, as it can be by pedestrians whenever desired.

The cross - head 2 is preferably made of metal, and its form and mode of structure 40 may be varied indefinitely so long as the essential features hereinbefore described are preserved.

What I claim as new, and desire to secure by Letters Patent, is— 45

In a swinging gate, the combination of the hinge-post 1 having the cross-head 2, the gate 4 having the permanent lower hinge 18, 19, the upper hinge composed of the hooked rod 3 attached to the post and the loop 5 engaging the hooked portion of the rod and fitting on opposite sides of the gate, and the rope extending from the cross-head over the gate and between the gate and the bars of the loop, substantially as described. 55

In testimony whereof I sign my name in the presence of two subscribing witnesses.

ANDREW A. DOWNEY.
